UNITED STATES PATENT OFFICE.

JACOB LONGYEAR AND DANIEL W. CLARK, OF GRASS LAKE, MICHIGAN.

IMPROVEMENT IN WIND-WHEELS.

Specification forming part of Letters Patent No. 222,515, dated December 9, 1879; application filed July 26, 1879.

To all whom it may concern:

Be it known that we, JACOB LONGYEAR and DANIEL W. CLARK, of Grass Lake, in the county of Jackson and State of Michigan, have invented certain new and useful Improvements in Wind-Wheels; and we do hereby declare that the following is a full, clear, and exact description of the construction and operation of the same, reference being had to the annexed drawings, making a part of this specification, and to the letters and figures of reference marked thereon.

Figure 1 of the drawings is a representation of a side elevation, partly in section, of our wind-wheel; and Figs. 2, 3, and 4 are detail views of the same.

The nature of our invention consists in the construction and arrangement of a windmill, as will be hereinafter more fully set forth.

The annexed drawings, to which reference is made, fully illustrate our invention.

A represents the bed-plate for the turn-table of the windmill. This bed-plate is provided with a hub, B, in which is made a circumferential groove, *a*, forming a track for the rollers *b b*, that support the turn-table, and on which it turns.

In the under face of the annular bed-plate A are made two radial dovetailed grooves, diametrically opposite to each other.

The bed-plate A is connected to the tower E by entering the wedge-shaped heads of the pins C C in said grooves, and the pins are securely bolted between the uprights E' of the tower.

D represents the turn-table, which is constructed to fit over the hub B; and forms a cover for the rollers *b*, said rollers being placed on the inner smooth ends of screws *d d*, passed through the turn-table at equal distances.

We use, preferably, four rollers; but we do not confine ourselves exclusively to this number.

The turn-table D is formed with arms, which constitute suitable bearings for the main shaft F. On this shaft the wind-wheel is secured, said wheel consisting of a hub, G, with radial spokes *e e*, cast fast therein. The spokes are connected by a rim or circle, *f*, and the wings H H are bolted to the same. The wings are made curved, as shown, and connected at the back by a circular brace, *h*. They are further

strengthened by a series of braces, *i*, running from a small hub or collar, *k*, on the end of the shaft to each wing, and there bent, and running to the back of the adjacent wing, as shown.

On the shaft F is fastened a collar, I, having a slotted flange, *m*, projecting from the same. To this flange the eccentric J is fastened by set-screws *n* passing through the slots in the flange. By this means the eccentric may be adjusted to regulate the stroke, as required.

Around the eccentric J is the usual strap or band and rod K, the latter being connected with the pump-rod L by a swivel-joint, *p*.

Opposite the inner end of the shaft F, through the arm of the turn-table, is fastened a rod or spindle, *s*, on the upper end of which is pivoted a hub, M. In this hub is screwed or otherwise fastened the shank of the main vane N, the normal position of which is in a line with the shaft F, it being held in such position by means of a spring, *t*, having one end fastened to the vane, and the other end wound around and fastened to the spindle *s*.

v is a brace secured to the vane N, and extending to the lower end of the spindle *s*, where the end of the brace is forked or split to fit in a groove on the spindle.

On the side of the hub M is pivoted a shank or lever, O, which carries at its upper end a small regulating-vane, P. Below the pivot-point the shank or lever O has a bend or curve, *w*, and to this is attached an arm, R, with weight S at the lower end. This weight holds the shank or lever O in a vertical position, with the curve or bend *w* resting against a curved arm, *a'*, projecting from the shaft bearing on the turn-table.

When the wind increases the vane P will move backward and downward more or less, which movement causes the curved part *w* to work against the arm *a'*, and this causes the hub M, with the main vane attached to it, to turn on the spindle *s*, and thus throw the wheel more or less out of the wind.

We claim—

1. The bed-plate A, formed with the hub B, having a circumferential groove, *a*, to receive the rollers *b*, for supporting the turn-table, substantially as herein set forth.
2. The turn-table D, constructed as de-

scribed, to form a cover for the rollers *b*, in combination with the grooved hub *B*, rollers *b*, and bolts *d*, substantially as set forth.

3. The pieces *C*, with wedge-shaped heads inserted in dovetailed grooves in the bed-plate *A*, for the purposes herein set forth.

4. The combination of the spindle *s*, hub *M*, and main vane *N*, substantially as herein set forth.

5. The spring *t*, in combination with the vane *N* and spindle *s*, for the purposes herein set forth.

6. The lever *O*, carrying the vane *P*, and piv-

oted to the side of the hub *M*, and provided with curved part *w* and weighted arm *R*, in combination with the curved arm *a'* and main vane *N*, substantially as and for the purposes herein set forth.

In testimony that we claim the above we have hereunto subscribed our names in the presence of two witnesses.

JACOB LONGYEAR.
DANIEL W. CLARK.
